UNITED STATES PATENT OFFICE.

JOSÉ BOTELHO D'AMARAL, OF FALL RIVER, MASSACHUSETTS.

DESIGN FOR A BUTTON, BADGE, MEDAL, EMBLEM, OR WATCHCASE.

53,118.

Specification for Design.

Patented Mar. 25, 1919.

Application filed December 10, 1918. Serial No. 266,125. Term of patent 7 years.

To all whom it may concern:

Be it known that I, JOSÉ BOTELHO D'AMARAL, a citizen of Portugal, residing at Fall River, in the county of Bristol and State of Massachusetts, have invented a new, original, and ornamental Design for Buttons, Badges, Medals, Emblems, and Watchcases, of which the following is a specification, reference being had to the accompanying drawing, forming part thereof.

The figure is a plan view of a button, badge, medal, emblem, or watchcase, showing my new design.

I claim:

The ornamental design for a button, badge, medal, emblem, or watchcase, as shown.

In testimony whereof I affix my signature.

JOSÉ BOTELHO D'AMARAL.
